UNITED STATES PATENT OFFICE.

WILLIAM CHESTER WOOD, OF BALTIMORE, MARYLAND, ASSIGNOR TO
THE CROWN CORK AND SEAL COMPANY, OF BALTIMORE, MARY-
LAND, A CORPORATION OF MARYLAND.

SODA-WATER-BOTTLING MACHINE.

No. 813,840.

Specification of Letters Patent.

Patented Feb. 20, 1906.

Application filed October 21, 1904. Serial No. 229,414.

To all whom it may concern:

Be it known that I, WILLIAM CHESTER Wood, a citizen of the United States, residing at Baltimore, in the State of Maryland, have invented new and useful Improvements in Soda-Water-Bottling Machines, of which the following is a specification.

Although my said improvements are applicable to other machines wherein syrups are delivered into bottles prior to the ultimate filling operation, they are specially adapted for use in machines wherein a suitable head carries syrup-delivering devices and also capping appliances, and are particularly desirable and effective in the well-known "Crown" soda-machines disclosed in United States Letters Patent issued to William Painter, July 26, 1898, No. 608,158, to which, if need be, reference may be had for further knowledge in this connection. A "Crown" soda-machine embodies a head carrying a pendent syrup-tube, and also a filling-chamber which is accessible to the liquids to be bottled and contains means for properly inclosing a bottle-head, and also devices for applying closures to bottles charged with gaseous liquids under pressure. Said machines also embody a double-contact gage located on a supporting-table beneath the syrup-tube and filling-chamber and in such position with relation thereto that while one of the two gaging contacts will generally cause one bottle to properly receive the syrup-tube the other gaging contact will simultaneously cause a second bottle to centrally enter the filling-chamber when the head and table are moved into coöperative relation. Bottles are, however, quite frequently so out of form that they cannot stand upright on their bases, and it is not uncommon for them to have necks out of line with the body, so that either or both of these variations from a perfect bottle result in serious injury sometimes to both the tube and the bottle. For partially obviating these results the syrup-tube has been provided with a long pointed tip to serve as a guide for entering imperfect bottles, and if a bottle be but little out of line said tips are fully effective; but if a bottle be materially out of line and standing on its base the tip is liable to strike and break the glass, and to avoid injury to the tips (as far as possible) they have

required the use of specially hard and expensive metals, as well as expensive features of construction. Moreover, such tips involve 55 the necessity for two or more small apertures for the passage of syrup, and they are liable to frequent obstruction due to solid sugary accretions, necessitating clearance, involving labor and delay. 60

It is now to be understood that among the objects sought and attained by the use of my invention are substantial economy in the construction of the syrup-tube, as well as an avoidance of expensive components, and also 65 a complete avoidance of the obstructive liability referred to, and in addition thereto to facilitate bottling operations as to speed and convenience and to practically obviate breakage of bottles. For attaining these ends I 70 have organized with the head of the machine a plain open-mouthed syrup-tube and a guide which is so proportioned, constructed, and arranged with relation to the end of the tube that the latter under no reasonable circumstances can ever strike the lip of a bottle on presentation for receiving syrup, and also so 75 that the bottle-head and neck may freely enter and occupy the guide, while inclosing the tube and permitting a free discharge of syrup 80 from a point well down in the neck directly into the body of the bottle, and to permit a second bottle (supported at the same horizontal plane) to occupy the filling-chamber and to receive its closure. It is, however, to 85 be also understood that substantially valuable results will accrue if my guide be employed with a pointed tube in avoidance of injury to it and to bottles, and hence I have provided for convenient and inexpensive attachment of the guide to the machine-head 90 with or without the substitution of a new tube for an old one.

After describing my improvements in detail in connection with the drawings the features deemed novel will be duly specified in appropriate clauses of claim hereunto annexed.

Referring to the drawings, Figure 1 illustrates a portion of the head of a machine 100 with my guide shown in section and also a portion of the bottle-supporting table with two bottles thereon, it being understood that the table and head are so organized with ap-

propriate mechanism that they are intermittently carried into coöperative relations. Fig. 2 is a top view of the guide detached. Fig. 3 is a view of the same in side elevation, and Fig. 4 illustrates a variation in the construction of a hanger-plate enabling vertical adjustment of the guide with relation to the mouth of the syrup-tube.

The head A of the machine and the table B are each only partially shown. The head has the usual filling and capping chamber *a*, shown in section, and also the syruping and valve attachment *b*, these being united by means of a clamping-nut *c* on a bolt projecting from the main portion of the head, at one side thereof. The mechanism for placing the table and head into coöperative relation is not here shown, it being immaterial whether the head or the table, or both, be movable toward and from each other.

At the one side of the filling-chamber is the pendent syrup-tube *d* in communication with a source of supply. A lever *e* is operatively connected with suitable valves which control the delivery of soda-water and syrup in a manner well known and as fully described in the hereinbefore-mentioned Letters Patent. Upon the table B there is the usual double-contact bottle-gage *f*, so located beneath the head that one of its contacts at *f'* will properly locate a bottle with reference to the filling-chamber, the other contact at *f''* in like manner locating a second bottle with its head and mouth in line with the syrup-tube, all as clearly indicated in the drawings. This bottle-gage depends for its accuracy upon peripheral contacts with bottles at or near their bases, these being seldom so out of form as to defeat the gaging intended. The mouth of the filling-chamber admits of quite wide variation in the position of bottles; but the syrup-tube demands accurate alinement with the center of the bottle-head, and while the base-gage may always serve its coöperative purpose with perfect bottles it cannot be relied upon with such imperfect bottles as cannot stand upright on their bases or those which, although having good bases, have necks more or less inclined from the axial line of the body of the bottle, and more especially such as may chance to embody both of the imperfections referred to.

The flaring annular guide C is intended to and does provide for a safe and reliable control of the heads and mouths of bottles, however imperfect.

As here shown, the guide is believed to be in its simplest form, having a largely-flared annular interior surface *g*, and it is provided with a short lateral arm *h*, terminating in a rectangular hanger-plate *h'*, by means of which it is so mounted upon the head of the machine as to encircle the tube and to have its center coincide with the center or axial line of the syrup-tube. The hanger-plate *h'* is slotted

either laterally or vertically, as shown in Figs. 3 and 4, so that the guide may be mounted by clamping the hanger-plate beneath the nut *e*, which, with its bolt, heretofore only served to unite the main portions of the head. The vertical slot admits of varied vertical adjustment of the guide, as may be desirable when applied to old machines; but with new machines the horizontal slot will be preferable, no variations being needed, and the bolt can then wholly support the guide instead of relying upon the clamping effect of the nut, as with the vertical slot. This construction of the guide, its arm, and its hanger-plate is a valuable feature, because it enables the guide to be readily and accurately mounted, even by an unskilled person and without any metal working whatever, to any of the many machines of the class indicated now out in service. The lateral arm is of such length and its hanger-plate of such thickness and the aperture in the plate is so accurately located that when mounted on the bolt already there and locked by the nut thereon the guide must occupy its proper relation to the syrup-tube, the operation of mounting involving only the momentary use of a wrench for loosening and tightening the nut.

It will be obvious that the guide may be composed of any suitable materials and that it may be variably constructed and mounted without departure from my invention; but, having durability, simplicity, and economy in view, brass is used, and the main body made separately from the hanger and provided with a rabbeted top, as shown, so that it can be easily lathed and readily and firmly coupled to the arm or hanger by expanding the top of the guide-body into a ring forming a part of the arm and having an appropriately-inclined inner surface, all as clearly indicated in Fig. 1.

As shown in Fig. 1, the syrup-tube is fully open at its lower end or mouth, permitting free and prompt delivery of syrup with little, if any, liability of obstruction by sugary accretions.

For securing the best results the guide should be so positioned as to locate the mouth of the tube in the plane of the smallest diameter of the guide, which at that point is sufficiently greater than the diameter of the bottle-heads as to afford ample annular space between the guide and tube for the free reception of a bottle-head. The length of the tube is such as to deliver syrup directly into the body of the bottle instead of against the side of the neck, this latter being quite objectionable; but if a shorter tube were used the guide might then be located wholly below the end of the tube and yet afford safety to the tube and bottles, and should the usual pointed tip be used the latter should be so located that it could never be hit by a bottle-head in entering the annular guide-space. In the separation

of a bottle from the guide a ready passage is afforded by providing the guide with a short upper flared surface g' , extending from the smallest diameter to the top of the guide, 5 thus insuring a smooth easy parting movement as between the guide and bottles.

In the operation of the machine a bottle is first charged with syrup and then moved laterally beneath the filling-chamber, already 10 containing a bottle-cap. A second bottle is then placed in the base-gage and the head and table placed into coöperative relation, so that as the first enters the filling-head the second bottle receives or incloses the syrup-tube. 15 The manipulation of the lever e causes a proper delivery of syrup to the second bottle and gas and water to the first. A further movement of the head or table (as indicated in dotted lines) results in capping the first, 20 and then the head and table are so separated as to free the two bottles, permit the one filled to be removed, the one with syrup moved laterally, and another placed in proper position below the syrup-tube, and so on as 25 already described, it being understood that the filling-chamber is capable of being tightly closed around the head and neck of a bottle.

Although bottles of a given set are intended to be as near equal in height as is practicable, they nevertheless vary considerably above and below the average height, and should one of the shortest bottles be within the filling-chamber and one of the longest at the syrup-tube this latter must have ample 35 clearance or head space when the head of the short bottle occupies its capping position. To make this clear, it may be assumed that the dotted line x , Fig. 1, fairly indicates the height to which heads of bottles of uniform 40 height would be carried during the final or capping operation. Should, however, the bottle at the cap chance to be especially short and the one at the table especially long, the head of the latter might need to even partly 45 enter the annular space indicated at the top of the tube, so as to avoid obstructing the rise of the other bottle to its proper capping

position, my guide rendering the entire upper portion of the tube available for head-space.

Having thus described my invention, I 50 claim—

1. In a soda-water-bottling machine, the combination with the filling-head restricted to the passage of gaseous liquids, of a pendent syrup-tube, and a flaring annular guide 55 carried at the one side by the head, encircling the tube, extending below its end and affording an annular space ample for the free reception and passage of a bottle-head and its neck, while inclosing the tube, substantially as described.

2. In a soda-water-bottling machine, the combination of a pendent open-mouthed syrup-tube, and a flaring annular guide carried in appropriate relation to the mouth of the 65 tube, adapted to freely receive the head and neck of a bottle, and to guide the head into line with and thereby cause a bottle to inclose said tube, and enable syrup to be directly and freely delivered into the body of 70 the bottle, substantially as described.

3. The flaring annular bottle-guide adapted to coöperate with a syrup-tube in a soda-bottling machine of the class indicated, by allowing the free passage of the heads of bottles guided by it, and provided with a lateral arm terminating in a hanger-plate rectangular to the arm and provided with an accurately-located aperture substantially as described, whereby without any special preparation therefor, the guide may be readily mounted in appropriate relation to the syrup-tube but wholly free therefrom, said aperture then being occupied by a bolt already in the head of the machine, and locked for service 85 by the nut already on said bolt.

In testimony whereof I have hereunto set my hand in presence of two subscribing witnesses.
